UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

RECEPTACLE AND BLANK THEREFOR.

Application filed October 20, 1920, Serial No. 418,274. Renewed December 3, 1925.

This invention relates to tapered or conical drinking cups or receptacles formed from paper or like material.

Many of the tapered drinking cups in use at the present time, are structurally weak with a consequent tendency to leak, at the bottom of the cup or, as will be termed, the apex. Attempts have been made in various ways to cure these defects, in most cases by reinforcing the cup at the apex with additional material. A reinforcement at the apex unless properly made usually results in the transfer of the weak point to other adjacent parts of the cup.

15 An object of this invention is to obviate these difficulties and contemplates the formation of a tapered cup in such a manner that not only is the apex reinforced and rendered water tight but the adjacent portions of the cup are strengthened and weakness minimized if not wholly eliminated.

A further object is to form the apices of the receptacles at a point within the body of the blanks and from solid stock.

25 An equally important factor is the use of a blank which may be economically cut from the stock, and one which is solid or integral, that is free from cuts or slits which weaken the blank and render it liable to destruction and likewise weakens the cup as well as tending to provide leaky joints.

To this end a blank substantially quadrantal in form is utilized which may be bent and folded flat or assembled and shaped upon a former into the finished article either by hand or by machinery, the apices of the receptacles being formed at points within the body of the blanks from solid stock and away from joints in the receptacles when formed.

The blanks are provided with suitable reinforcing portions or tabs and the arrangement is such that when the blanks are folded the reinforcing parts surround the apices and adjacent parts of the cups, the edges of the reinforcing parts contacting with the cups and preferably being disposed diagonally to the plane of the cups, providing a gradual reinforcement of the cup toward its apex.

Instead of using a solid blank for the cup including the reinforcement as before described, the cup may be formed from two blanks, one forming the major portion or body of the cup and the other the sealing

strip and reinforcement for the apex. In this case neither the blank which forms the body of the cup nor the blank which forms the sealing strip is cut or slit but may be said to be solid or integral within themselves. In forming the cup the sealing strip is utilized to unite the edges of the major or body blank and is bent in such a manner as to reinforce and strengthen the lower part and apex of the cup.

Further details of the invention will hereinafter appear and reference will be made to the accompanying drawings in which

Fig. 1 is a perspective view of the one form of cup completed or assembled.

Fig. 2 represents the appearance of the cup of Fig. 1 during a stage of its formation upon a former.

Fig. 2^a is a stage in the formation of the cup in flat form.

Fig. 3 is a plan view of the blank from which the cup is made.

Fig. 4 shows the reinforcement of a larger part of the cup by the use of a larger reinforcing portion or tab.

Fig. 5 is a perspective view of a cup formed from a slightly different blank, which is well adapted to be completely formed while flat.

Fig. 6 illustrates a stage in the formation of the cup.

Fig. 6^a is a side view showing completed cup in flat form.

Fig. 7 is a top view of Fig. 6.

Fig. 8 is a plan view of the blank from which the cup shown in Figs. 5 and 6 is formed.

Fig. 9 is a perspective view showing a cup formed from two blanks.

Fig. 10 illustrates a stage in the formation of the cup shown in Fig. 9.

Fig. 11^a is a plan view showing the blank which forms major or body portion of the cup; and Fig. 11^b is a plan view showing the blank which forms the sealing strip and reinforcement for the cup.

Fig. 12 is a perspective view showing the use of a sealing strip, wider than that of Figs. 9 to 11^b.

To form the cup shown in Fig. 1 a blank substantially quadrantal in form is utilized. The edge 2 of the blank is in the form of an arc struck from the center or point 3.

The edge or flange 4 extends from below the center 3 outwardly and meets the curved

edge 2 and may be consequently termed the chord. The edge 5 has an outer portion 6, which projects radially from the center and a portion which forms a tab 7. The portion 5 or tab 7 is defined by a compound curve having the concaved portion 8 and convex portion 9. The curved portion 8 unites the outer portion 6 with the convex portion 9 and the convex portion 9 unites the edge 4 and concaved portion 8.

To form the cup shown in Fig. 1 adhesive is applied to the edge 4 and portion 7 of the blank and the blank may then be assembled upon a former 10, shown in dotted line in Fig. 2, the point 3 being positioned at the apex of the former. The tab 7 is then reversely bent along the line 11 toward the body or major portion of the blank. It will be seen that by shaping the tab as before described the blank is then gradually reinforced toward the apex. The edge 4 is then caused to overlap the edge 6 and tab 7 and the edge 4 and tab 7 are then sealed to the blank, taking the form of a spiral as shown in Fig. 1. It will be observed, see Fig. 1, that the edge 4 and tab 7 when the cup is formed are not coincident but are separated thereby causing a gradual reinforcement of the cup and to a greater extent than if the reinforcement were abruptly made.

Fig. 4 illustrates a reinforcement of a larger portion of the cup by providing larger overlapping and tab portions. Otherwise the blank and the cup formed therefrom is substantially the same as that of Figs. 1, 2 and 3.

Instead of forming the cup upon a former as just described the cup may be assembled in flat form. In this case the adhesive is applied in the manner before described and the blank is folded upon itself along the dotted line 12; the edge 4 is then folded along the dotted line 13 so as to overlap the edge 6 and the tab 7 and sealed, the tab 7 meanwhile having been folded reversely upon the body of the blank along the line 11. This folding produces an overlapping portion 14 see Fig. 2^a and this portion 14 is then bent along the line 15 and sealed upon the opposite face of the blank. The cup having thus been formed may be opened to final form for drying.

Figs. 5 to 8 inclusive illustrate a blank and cup which is particularly adapted to be formed or assembled in flat form.

In this case an integral blank substantially quadrantal in form is utilized being defined by the edges 16, 17 and 18 the latter being curved and preferably struck from the center 19. The edges 16 and 17 join and project outwardly from a point slightly below the center 19 and meet the curved edge 18.

To form the cup from this blank adhesive is applied to a narrow portion of the blank 65 along the edges 16 and 17, and the blank is

then bent upon itself along the line 20 and the edges 16 and 17 sealed forming the sealed portion 21.

The blank is then bent adjacent the sealed edges 16 and 17, now termed the sealed portion, along the line 22 and sealed to the major portion or body of the blank.

As a result of this folding and sealing of the sealed portion 21 a part 23 of the portion 21 extends beyond the blank adjacent the apex, see Fig. 6. This part 23 is then folded along the line 24 and sealed to the opposite side of the blank thereby forming the cup, see Fig. 6^a. It will be observed in this case, like the cup of Fig. 1 there is a gradual reinforcement of the cup toward its apex, see Fig. 5, this being promoted by the tapering of the edge 16 in respect to the line 22 and edge 17 when the edge 16 is sealed adjacent the latter. The cup may then be opened as illustrated in Fig. 5 for drying. If desired, however the blank may be assembled upon a former in a manner similar to that described in connection with Figs. 1 to 4.

The cup shown in Fig. 9 is formed from two blanks, each integral in themselves, the body of the cup being formed from the major blank 25 which is sealed and reinforced by the minor blank 26.

The blank 25 has the characteristics of the development of a cone and is defined by the edges 27, 28 and 29, the latter being curved. To form the cup adhesive is applied to the minor blank 26 and the major blank 25 is folded upon itself along the line 30. The two blanks are then brought together the apex 31 of the folded blank 25 being located at the point 32 of the blank 26 and the edges 27 and 28 along the line 33, and united by folding the blank 26 along the line 33 and sealing the edges 34 and 35 to opposite faces of the blank 25. When this is accomplished a portion 36 of the minor blank will project beyond the major blank adjacent its apex see Fig. 10 and in a manner similar to the part 23 of Fig. 6. This portion 36 is then folded along the line 37 and then along the line 38 and sealed to complete the cup. When the cup is expanded the edges of the minor blank 26 taper with respect to the edges 27 and 28 and serve to gradually reinforce the cup toward its apex, where the minor blank terminates in the form of a spiral, see Fig. 9.

It will be observed that in the several types of receptacles above described, their apices are formed at the centers or points 3, 19, and 32, which are located in the body of the blanks and away from points where the receptacles are formed. The apices are thus formed from solid stock which acts to strengthen the receptacles at this point and to prevent leaking.

Fig. 12 shows the use of a wider minor blank which acts to provide a larger rein-

forcement of the cup. The manner of assembling the cup of this figure is the same as that of assembling the cup of Fig. 9.

The several cups above described may be assembled from blanks of waterproof material or the cups may be waterproofed after completion.

Having thus described the invention what is claimed is:

10 1. A blank for a tapered receptacle provided with edges of different configuration formed as a part of a solid blank and adapted to be sealed to each other to form a sealing portion, said sealing portion being 15 adapted to be folded and curled around the apex of the receptacle and sealed to the major portion of said blank.

2. A paper cup blank of substantially quadrantal form having a curved edge and 20 two radial straight edges, integrally connected flanges formed on said straight edges to the outside of the meeting point of said straight edges, said flanges adapted to overlap one another and be curled around the 25 apex of the cup when the cup is formed.

3. A paper cup blank of substantially quadrantal form having a curved edge and two intersecting straight radial edges, a straight flange integrally formed along the 30 entire length of one of said straight radial

edges, and a tab integrally formed along a portion of the other straight radial edge.

4. A cup blank of substantially quadrantal form having a curved edge and two intersecting straight radial edges, and integrally 35 connected extensions of different configuration integrally formed on both of said straight radial edges.

5. A cup blank of substantially quadrantal form having a curved edge and two 40 straight radial edges intersecting at a point within the blank, a straight extension integrally formed along the entire length of one of said straight edges, and a tapered extension integrally formed along the other 45 straight edge.

6. A cup blank having a curved edge and two straight edges, a tapered extension integrally formed on one of said straight edges adapted to be bent to lie against the outer 50 surface of the cup blank, and a second extension integral with the other straight edge and integral with said tapered extension, said second extension adapted to overlap the tapered extension and be curled therewith 55 around the apex of the cup when the blank is formed into a cup.

In testimony whereof I affix my signature.

CESARE BARBIERI.
